UNITED STATES PATENT OFFICE.

ALBERT D. RAY, OF CLEVELAND, OHIO.

DESIGN FOR A PENCIL SHARPENER.

Application filed December 17, 1927. Serial No. 24,516. Term of patent 14 years.

To all whom it may concern:

Be it known that I, ALBERT D. RAY, a citizen of the United States, residing at Cleveland, in the county of Cuyahoga and State of Ohio, have invented a new, original, and ornamental Design for Pencil Sharpeners, of which the following is a specification, reference being had to the accompanying drawings, forming part thereof.

Figs. 1 and 2 of the drawing show a front and side elevational view respectively of the design of my invention.

I claim:

The ornamental design for a pencil sharpener substantially as shown.

In testimony whereof, I hereunto affix my signature this 14th day of December, 1927.

ALBERT D. RAY.
